ENGINE HAVING OIL PAN WITH DEFLECTION VANES

Richard K. Shier, Westland, Mich., assignor to General Motors Corporation, Detroit, Mich., a corporation of Delaware

Filed July 31, 1967, Ser. No. 657,363

U.S. Cl. 184—6 11 Claims
Int. Cl. F01m 11/06; F16n 7/36; F02f 7/00**ABSTRACT OF THE DISCLOSURE**

An engine includes an oil pan having a sump portion at one end and a shallow portion at the other separated by a raised transverse tunnel arranged to provide clearance for a power output shaft to pass close to the longitudinal axis of the engine crankshaft. The transverse tunnel extends close to the center bearing cap and above the lowest positions reached by the adjacent crank throws and counterweights of the crankshaft. Flow directing diagonal vanes are arranged along the floor of the pan shallow portion sweeping back toward the raised tunnel. The vanes receive oil swept transversely across the pan shallow portion by rotation of the crankshaft and deflect the oil over the raised tunnel into the sump so as to prevent an excessive accumulation of oil in the pan shallow portion. Two alternative ways of forming the ribs are disclosed. Additional baffle means to prevent oil sloshing from the sump and forward of the shallow portion are also disclosed.

Background of the invention

This invention relates to internal combustion engines and, more particularly, to an engine having an oil pan with flow-directing vanes and baffle members to direct oil over a raised central portion of the pan and retain it in a sump portion.

In internal combustion engines of conventional construction, it is common practice to provide a removable oil pan located beneath the crankshaft and reciprocating parts of the engine. The oil pan commonly includes a sump portion in which the major portion of the lubricating oil charge for the engine is contained and from which it is drawn by a lubricating oil pump for delivery to the engine oil system. The oil is used for lubricating the various bearings and moving parts of the engine and then drains back from the interior portions of the engine to the engine oil pan, the floor of which is normally slanted so as to return the oil to the sump portion of the pan for reuse or storage.

In certain engine applications, however, such as in certain well known front wheel drive automobiles, the vehicle arrangement requires a transverse power output shaft to pass closely beneath the central portion of the engine. In order to accommodate such an arrangement, it is known in the art to provide an oil pan having a raised tunnel portion extending transversely across the pan and separating the sump portion in the rear of the pan from a relatively shallow portion in the front of the pan. To provide maximum clearance for the transverse shaft, the raised portion of the pan is located between crank throws of the engine crankshaft and extends above the lowest point reached by the crank throws and counterweights during operation of the engine. In oil pans of this type, the raised tunnel portion creates a dam which tends to trap excessive amounts of oil in the shallow front portion of the pan. To prevent this, it is known to provide baffle means to receive oil swept to the side of the pan by the rotating crankshaft and associated components and to carry the oil in the manner of an eave trough along the

2

side of the pan and over the raised portion back to the sump.

Summary of the invention

The present invention relates to an oil pan of the type described, but having simple yet novel means of moving oil from the shallow portion of the pan over the raised tunnel and into the sump portion to prevent an excessive accumulation of oil in the shallow portion. This is accomplished by the provision of diagonal flow-directing vanes along the bottom of the pan shallow portion. The vanes receive oil which is swept transversely across the shallow portion of the pan by the rotating crankshaft and direct the oil rearwardly over the raised tunnel and into the sump. Thus, the present arrangement makes use of the direct impingement of the oil on the vanes and deflection by the vanes in the direction of the sump as opposed to relying on collection of the oil in gravity distributing baffle means of the prior art.

In addition, in order to prevent oil from sloshing out of the sump and into the shallow portion due to rapid accelerations or decelerations of the vehicle, a horizontal baffle is provided extending from the raised tunnel horizontally over the adjacent part of the sump portion. An additional baffle member is provided at the front of the pan shallow portion to prevent excessive amounts of oil from sloshing against the front crankshaft oil seal.

The present arrangement has been shown to be a simple yet effective means for accomplishing the desired purpose of maintaining an adequate supply of oil in the engine sump and preventing an excessive accumulation of oil in the front shallow portion of the oil pan. These and other advantages of the present invention will be more apparent from the following description and drawings of specific embodiments of the invention disclosed in detail hereinafter.

Brief description of the drawings**In the drawings:**

FIGURE 1 is a fragmentary cross-sectional view of an engine and oil pan assembly embodying the invention;

FIGURE 2 is a top view of the oil pan of FIGURE 1 taken generally along the line 2—2 of the figure;

FIGURE 3 is a transverse cross-sectional view taken generally along the line 3—3 of FIGURE 2;

FIGURE 4 is a fragmentary top view of an oil pan similar in other respects to that of FIGURE 2, but showing an alternative embodiment of the flow-directing vanes;

FIGURE 5 is a longitudinal cross-sectional view of the embodiment of FIGURE 4 taken generally along the line 5—5 of the figure; and

FIGURE 6 is a transverse cross-sectional view of the oil pan of FIGURES 4 and 5 taken generally along the line 6—6 of FIGURE 5.

Description of the preferred embodiments

Referring now to the drawings, FIGURE 1 discloses an internal combustion engine generally indicated by numeral 10 and having a frame 12 in which is rotatably carried a crankshaft 14. The crankshaft includes a plurality of longitudinally spaced crank throws 16 to which are attached the usual connecting rods 18. Adjacent the crank throws are a number of counterweights 20 for balancing the crankshaft and the reciprocating parts of the engine connected to the crankshaft.

The crankshaft is supported in the engine frame at journals 22 spaced intermediate each of the crank throws and at the ends of the crankshaft by a plurality of bearing caps 24 extending thereunder. The crank throws 16 and the counterweights 20 are located eccentric to the center line of the crankshaft so that, at their lowest positions

reached during rotation of the crankshaft, they extend substantially below the lowest surfaces of bearing caps 24.

Sealingly secured to the engine frame 12 and extending the length of the engine beneath the crankshaft is an oil pan generally indicated by numeral 26. The oil pan includes a relatively deep sump portion 28 located under the rear portion of the engine and a shallow portion 30 located under the front portion of the engine. These portions are defined in part by side walls 32 connected by a floor 34 which, in the shallow portion of the pan, closely surrounds the engine crankshaft, having a minimum of clearance from the lower positions of the crank throws and counterweights.

Between the sump portion 28 and the shallow portion 30, the pan floor 34 includes an arcuately shaped raised tunnel portion 36 extending transversely across the pan to provide clearance through which a power output shaft 38 extending from final drive housing 40 (indicated by phantom lines) may pass transversely under the engine near the location of the center main journal. To permit the output shaft to pass as closely as possible to the crankshaft axis, the raised portion 36 of the oil pan floor is located intermediate the center pair of crank throws and extends above the lowest position of the crank throws and counterweights to a point close to the center main bearing cap. The raised floor portion 36, extending across the center of the pan, creates a dam which tends to prevent oil collecting in the shallow portion 30 of the pan from returning to the sump portion 28 at the rear of the pan. Without additional means to return the oil to the sump during operation of the engine, an excessive volume of oil would collect in the shallow portion of the pan and would be whipped into an aerated foam by the rotation of the crank throws and counterweights through the oil. Retention of this oil in the pan shallow portion would also tend to lower the level of oil in the sump portion 28 and starve the engine lubricating oil system.

To overcome this problem, diagonally extending flow-directing vanes 42 are provided along the floor of the pan shallow portion. In the embodiment of FIGURES 1-3, the vanes take the form of upwardly extending ribs formed in the sheet metal of the oil pan floor. The ribs are formed with their front sides 44 forming a relatively shallow angle with the floor 34, while their rear sides 46 extend upwardly from floor 34 at a sharp angle approaching 90°. In this way, the rear sides 46 are arranged to receive oil thrown transversely across the oil pan floor and to direct it rearwardly so that it passes over tunnel portion 36 and into the sump 38.

In the alternative embodiment of FIGURES 4-6, a differing arrangement of vanes is shown. In this embodiment, a deflector member 48 is secured, as by spot welding, to the shallow portion of the oil pan floor which contains no ribs. Instead, the vanes are formed by upwardly vent portions 50 of deflector member 48. The vane portions 50 are angled rearwardly toward tunnel portion 36 so as to effectively trap the oil swept transversely across the oil pan floor and direct it rearwardly over the tunnel portion and into the sump.

The diagonal vanes, which extend upwardly and rearwardly along the shallow portion of the oil pan floor, effectively clear the pan shallow portion of excessive accumulations of oil under the majority of operating conditions. During sudden stopping movements or negative accelerations of the vehicle, however, it could be possible for excessive amounts of oil to slosh forward out of the sump and over the tunnel portion 36 forming temporary excessive accumulations in the shallow portion of the pan. Also, during such movements, oil in the pan shallow portion may be driven forward against the seal 52 located on the front portion of the crankshaft. In order to prevent such occurrences, a horizontal baffle member 54 is disposed over the front part of sump 28, being secured along tunnel portion 36 and the adjacent sides of the oil pan. This baffle includes a stiffening rib 56 and acts to

5 prevent oil from sloshing out of the sump during stopping movements of the vehicle. In addition, at the front of the pan shallow portion, a vertical baffle member 58 is located. This baffle is secured to the sides of the oil pan and provides an opening 60 between its lower edge and the oil pan floor to permit proper drainage from the front portion of the engine into the pan shallow portion. The vertical baffle 58 is effective to prevent the sloshing forward of excessive amounts of oil in the pan shallow portion whenever quick stops of the vehicle occur.

10 While the present invention has been disclosed by two specific embodiments showing in detail the best known means for carrying out the invention, it should be apparent that numerous changes could be made by those skilled in the art within the spirit and scope of the invention which is, accordingly, to be limited only by the language of the following claims.

I claim:

1. An oil pan for an internal combustion engine comprising a relatively shallow portion, a relatively deep sump portion and a transversely extending dam portion separating said shallow portion from said deep portion, and means to direct oil from said shallow portion over said dam portion and into said sump portion, said means including a plurality of upwardly extending diagonal vanes arranged along the bottom of said shallow portion to intercept and direct toward said sump portion oil thrown transversely against said vanes as a result of the effect of the moving parts of the engine.

20 2. The combination of claim 1 wherein said vanes extend diagonally at an angle of about 45 degrees from the longitudinal axis of the oil pan.

3. The combination of claim 1 wherein said vanes comprise ribs stamped into the sheet metal bottom of the oil pan, said ribs having the sides thereof toward said dam portion extending upwardly at a sharp angle with respect to the bottom pan surface.

40 4. The combination of claim 1 wherein said pan includes a sheet metal deflector member secured in the bottom of said shallow portion and said vanes are formed by upwardly bent portions of said deflector member.

5. An oil pan for an internal combustion engine comprising a relatively shallow portion, a relatively deep sump portion and a transversely extending dam separating said shallow portion from said deep portion, said dam being formed by a raised portion extending across the bottom of said pan to provide clearance for a member to pass transversely thereunder and means to direct oil from said shallow portion over said raised portion and into said sump portion, said means including a plurality of upwardly extending vanes arranged diagonally at an angle of around 45 degrees from the longitudinal axis of the oil pan and along the bottom of said shallow portion to intercept and direct rearwardly oil thrown transversely against said vanes as a result of the effect of the moving parts of the engine.

50 6. The combination of claim 5 and further including a generally horizontal baffle member extending from said raised portion over the adjacent part of said sump portion to prevent oil in said sump portion from sloshing over into said shallow portion.

60 7. In combination with an internal combustion engine having a crankshaft rotatably carried in the lower portion thereof, said crankshaft having a plurality of longitudinally spaced eccentric portions,

65 an oil pan closing said engine lower portion adjacent said crankshaft and having at one end a sump portion to contain a charge of lubricating oil and at the other end a relatively shallow portion having a floor spaced from said crankshaft eccentric portions, said oil pan including a raised portion of said floor extending transversely across said pan between said sump portion and said shallow portion to provide clearance for a member to pass transversely under said pan and

- a plurality of upwardly extending diagonal vanes arranged on said shallow portion floor to intercept oil swept transversely thereacross by said crankshaft eccentric portions and direct said oil over said raised portion and into said sump portion.
8. The combination of claim 7 wherein said eccentric portions comprise crank throws and counterweights, said raised portion being spaced longitudinally intermediate two of said crank throws and extending upwardly above the lowest point reached by at least one of said crank throws and counterweights.

9. The combination of claim 8 wherein said vanes comprise ribs stamped into the sheet metal bottom of said shallow portion, said ribs having the sides thereof toward said raised portion extending upwardly at a sharp angle with respect to said bottom surface.

10. The combination of claim 8 wherein said pan includes a sheet metal deflector member secured along said shallow portion bottom and said vanes are formed by

upwardly bent portions of said deflector member.

11. The combination of claim 10 wherein said pan includes a generally horizontal baffle member extending from said raised portion over the adjacent part of said sump portion to prevent oil in said sump portion from sloshing over into said shallow portion.
